CLAIM

The ornamental design for a sample preparation cartridge, as shown and described.

DESCRIPTION

FIG. 1 is a front perspective view of a sample preparation cartridge in accordance with the present invention.

FIG. 2 is a rear perspective view of the sample preparation cartridge of FIG. 1.

FIG. 3 is a left side view of the sample preparation cartridge of FIG. 1.

FIG. 4 is a right side view of the sample preparation cartridge of FIG. 1.

FIG. 5 is a rear view of the sample preparation cartridge of FIG. 1.

FIG. 6 is a front view of sample preparation cartridge of FIG. 1.

FIG. 7 is a top view of the sample preparation cartridge of FIG. 1; and,

FIG. 8 is a bottom view of the sample preparation cartridge of FIG. 1.

The broken lines are included for the purpose of illustrating portions of the sample preparation cartridge that form no part of the claimed design.
